UNITED STATES PATENT OFFICE.

THOMAS H. SYMINGTON, OF ROCHESTER, NEW YORK, ASSIGNOR, BY MESNE ASSIGNMENTS, TO THE T. H. SYMINGTON COMPANY, OF NEW YORK, N. Y., A CORPORATION OF DELAWARE.

DRAFT RIGGING.

1,409,039.

Specification of Letters Patent.

Patented Mar. 7, 1922.

Application filed May 20, 1918. Serial No. 235,526.

To all whom it may concern:

Be it known that I, THOMAS H. SYMINGTON, a citizen of the United States, residing at Rochester, in the county of Monroe and State of New York, have invented certain new and useful Improvements in Draft Rigging; and I do hereby declare the following to be a full, clear, and exact description of the invention, such as will enable others skilled in the art to which it appertains to make and use the same.

The invention relates to draft rigging for railway cars and more particularly to novel means for greatly increasing the capacity of draft rigging to absorb shocks delivered thereto by the inward movement of the coupler under buffing blows. To this end, the main features of my invention, generally stated, comprise a rigid back-stop and draft sill, the casting provided with a friction face or surface, and spring-actuated wedging and wedging friction members interposed between the said back stop and a movable element of the draft rigging, said friction members only being operable under extreme buffing shocks.

There are features of the invention which relate to the form and manner of operation of the device, as will be apparent from the more detailed description of the invention when taken in connection with the accompanying drawings which have been chosen to illustrate one form of my device, and in which—

Figure 1 is a top plan view partially in section of a draft rigging embodying my invention.

Figure 2 is a central longitudinal vertical section of the device as shown in Figure 1, portions of the device being in elevation.

Figure 3 is a fragmentary plan view partially in section of the friction mechanism, the resistance mechanism being omitted.

Figure 4 is a longitudinal central sectional view showing the relative positions of the wedging and wedging friction mechanism under full buff, and

Figures 5 and 6 are respectively perspective views of a wedging friction member and the wedge member respectively.

Throughout the specification and drawings like parts are designated alike.

In the drawings the numerals 1, 1, designate portions of the center or draft sills of a car to which the draft rigging is connected.

The cheek-plates 2, 2, in the form of draft rigging chosen for illustration, are connected to the outer faces of the respective sills by means of rivets 3, 3 or other suitable fastening means. Each cheek-plate is provided with a pair of longitudinally extending slots 4 and 5, the said slots 4, being in alinement with slots 6 in the yoke 7 and with the slot 8 in the coupler 9. A key 10 is adapted to extend through the alined slots in the several elements and serves to operatively connect the said coupler and yoke. The said key normally contacts the rear wall of the coupler slot 8 and the forward walls of the yoke slots 6, and is so located in the slots 4 of the said plates as to have a greater travel rearwardly than forwardly.

Passing through the slots 5 in the cheek-plates 2 and through the elongated slots 11 in the yoke 7 and through the slots 12 in the front follower 13 is the key 14. This key normally contacts the rear wall of the follower slot 12 and the forward walls of the slots 5, 5 in the cheek-plates, and serves to transmit the draft strains imparted to the said follower to the cheek-plates 2. Seated against the rear end of the yoke 7 is the rear follower 15 which may be and preferably is of H-shape having upper and lower projecting arms 16. The upper arms 16 extend over the yoke and serve to maintain the follower in position.

Interposed between the front and rear followers 13 and 15 is the cushioning or resistance mechanism 16 which may be of any desired form, a friction mechanism, for convenience, being diagrammatically illustrated by dotted lines.

Bridging the space between the draft sills and rigidly connected to the same is the combined back stop and tie casting 17. The said casting is spaced rearwardly from the inner end of the yoke and is provided with a transversely extending face or surface 18. The said surface is formed by the front face of the transversely extending web 19. This web is connected to the side walls 20 of the said casting and is braced and strengthened by the rearwardly extending ribs or flanges 21 and 22.

To the inner faces of the sills 1, adjacent the rear end of the yoke 7, are connected the stop members 23, the inner ends of which terminate in line with the rear face of the yoke when the same is in normal position.

105

110

2

Between the rear end of the yoke 7 and the face 18 of the stop casting is arranged the auxiliary resistance mechanism 24 which may and preferably does comprise a 5 wedging block 25, a plurality of wedging friction blocks 26, 26 and means extending transversely of the draft sills for yieldingly resisting the movement of said wedging and wedging friction blocks, said means serving 10 also to maintain said block in operative position. The wedging block 25 is provided with a yoke engaging face 27, and is adapted to seat at its ends against the rear faces of the stop members 23. On its opposite 15 face the block 25 is provided with a plurality of converging wedging faces 28, 28, said faces being interrupted by a plurality of rearwardly and transversely extending ribs or flanges 29 which are provided with 20 flat inner faces. Intermediate a pair of the ribs 29 the wedging faces 28 are cut away as at 31 to provide a bolt receiving socket or recess 32. The wedging friction blocks 26 each comprise a plurality of connected walls 25 33 and 34 which are arranged substantially at right angles to each other, the said walls being connected adjacent their top and bottom by webs or flanges 35 and 36, respectively. Intermediate the said webs 35 and 30 36 the walls are also connected by a plurality of webs 37 and 38. The last-named webs are spaced from the flanges 35 and 36 respectively a distance equal to the width of one of the ribs 29. Intermediate the webs 37 and 38 the wall 33 is provided with 35 a bolt receiving opening 39. In position the walls 34 of the said blocks 26 are adapted to frictionally engage the face 18 of the said stop casting, and the outer faces of the webs 40 35 to 38, inclusive, are adapted to engage the wedging faces 28 of the block 25 intermediate the ribs 29. The lateral edges of the ribs 29 are adapted to engage the inner faces of the walls 33 to limit the approach 45 of the wedging blocks 26. The faces 30 of the said ribs 29 are in normal position of the several parts spaced from the adjacent faces of the walls 34, but are adapted to contact the same to limit the movement of the 50 wedging block 25. The tongue and groove connection between the block 25 and the blocks 26 not only maintains these blocks in correct position during the operation thereof, but also serves as a means for directly 55 transmitting to the stop casting 17 the loads transmitted to the draft rigging in excess of the capacity of both the cushioning member 16 and the auxiliary member 24. It will be noted from the disclosure that when the 60 faces 30 of the ribs 29 engage the faces of the walls 34 that the entire auxiliary mechanism is locked against movement and acts as a solid column to transmit the excessive loads to the stop casting.

65 The blocks 25 and 26 are carried by a

transversely extending rod 40 which is passed through the sills and through the openings 39 in the said blocks 26. The outer ends of the said rod are provided with adjustable washers 41, and interposed between 70 each washer and the adjacent block 26 is a spring 42 and a thimble block 43. The said thimble blocks extend through the sills and bear at one end against the wall 33 of the blocks 26 and at the opposite end against 75 the inner end of the spring 42. The washers and the thimble blocks form spring seats for the respective ends of the springs 42. From the foregoing description it will be clear that an inward movement of the yoke from its 80 normal position, which will be permitted by the rearward elongation of the slots 4 and 5 in the cheek-plates, will be resisted by the springs 42 and by the friction generated between the block 25 and the blocks 26 and between the latter and the stop casting 17. The auxiliary friction device is preferably so adjusted that it will remain substantially stationary and act as a rigid abutment for the yoke until the cushioning mechanism within 85 the same is compressed solid, after which the auxiliary mechanism will come into action to absorb excessive strain beyond the capacity of the draft rigging cushioning mechanism.

90 It will be readily apparent to those skilled in this art that my device adds greatly to the capacity of the draft rigging to absorb buffing shocks, and provides a device of high capacity which occupies a relatively small 100 amount of space and which in no way interferes with the usual underframe arrangement.

Having now fully described my invention, although it is to be understood that by 105 the foregoing I do not intend to limit the scope of my invention, and that the terms used are to be understood in their descriptive and not in their limiting sense, what I claim and desire to secure by Letters Patent is: 110

1. In a draft rigging the combination with draft sills, of a rigid combined back stop and tie casting, a coupler, a cushioning mechanism therefor, means for operatively connecting said coupler and cushioning 115 mechanism and means interposed between said cushioning mechanism and said tie casting and including members which slidably engage the latter, said means being adapted to afford a progressively increasing resistance to buffing shocks which exceed the capacity of said cushioning mechanism.

120 2. In a draft rigging the combination with draft sills, of a coupler, a yoke connected thereto, a cushioning mechanism within the 125 yoke and adapted to absorb the normal load of buffing and draft, a combined back stop and tie casting connected to the said draft sills and spaced from the said yoke and means interposed between the said yoke and 130

- back stop and slidably engaging one of said elements for absorbing buffing loads in excess of the capacity of the said cushioning mechanism.
5. In a draft rigging the combination with draft sills, of a combined stop and tie casting connected thereto, a yoke, and transversely acting means involving friction producing elements interposed between said 10 yoke and casting, the latter having a flat face cooperating with said transversely acting means, said means being adapted to contact the said casting and adapted to resist rearward movement of said yoke from normal 15 and means for supporting said first named means in position.
4. In a draft rigging the combination with draft sills, of a horizontally disposed yoke, a cushioning mechanism within the same, a 20 stop casting positioned intermediate the said sills and in rear of said yoke, and means for opposing the rearward movement of the said yoke, said means including a wedge block contacting the said yoke, and a plurality of wedging blocks interposed between said first 25 named block and said casting and adapted to frictionally engage both of said members.
5. In a draft rigging, the combination with a pair of draft sills, a yoke and a back stop spaced from the rear end of said yoke, said 30 back stop being adapted to connect the said sills, of means interposed between said yoke and back stop and slidably engaging the latter, said means comprising a wedge block, and a plurality of laterally moving wedging 35 friction blocks, means for resisting the movement of said blocks, said blocks and wedge being provided with intermeshing tongue and groove connections.

In testimony whereof I affix my signature. 40

THOMAS H. SYMINGTON.
